CLAIM

The ornamental design for a handle, as shown and described.

DESCRIPTION

FIG. 1 is a front, left perspective view of a handle of the new design;

FIG. 2 is a front elevational view of the handle of FIG. 1; FIG. 3 is a left side elevational view of the handle of FIG. 1;

FIG. 4 is a right side elevational view of the handle of FIG. 1;

FIG. 5 is a top plan view of the handle of FIG. 1;

FIG. 6 is a bottom plan view of the handle of FIG. 1;

FIG. 7 is a cross-sectional view of the handle of FIG. 1, taken along the line 7-7 in FIG. 2, showing the contour of a portion of the exterior surface of the handle;

FIG. 8 is a cross-sectional view of the handle of FIG. 1, taken along the line 8-8 in FIG. 2, showing the contour of another portion of the exterior surface of the handle;

FIG. 9 is a cross-sectional view of the handle of FIG. 1, taken along the line 9-9 in FIG. 2, showing the contour of another portion of the exterior surface of the handle;

FIG. 10 is a cross-sectional view of the handle of FIG. 1, taken along the line 10-10 in FIG. 2, showing the contour of another portion of the exterior surface of the handle;

FIG. 11 is a cross-sectional view of the handle of FIG. 1, taken along the line 11-11 in FIG. 2, showing the contour of another portion of the exterior surface of the handle;

FIG. 12 is a cross-sectional view of the handle of FIG. 1, taken along the line 12-12 in FIG. 2, showing the contour of another portion of the exterior surface of the handle;

FIG. 13 is a cross-sectional view of the handle of FIG. 1, taken along the line 13-13 in FIG. 2, showing the contour of another portion of the exterior surface of the handle; and,

FIG. 14 is a cross-sectional view of the handle of FIG. 1, taken along the line 14-14 in FIG. 2, showing the contour of another portion of the exterior surface of the handle.

The portions of the Figures shown in broken lines are not part of the claimed design and are for illustration only.
